DIE CAST LOOSE-LEAF RING METAL FRAME

Pete O. Derringer, St. Louis, Mo., assignor to
Loose Leaf Metals Company, St. Louis, Mo., a
corporation of Missouri

Application July 29, 1950, Serial No. 176,699

2 Claims. (Cl. 129—24)

1

The present invention relates generally to loose leaf ring binders, and more particularly to a die cast ring metal frame for loose leaf binders.

In brief, the novel device herein described includes two identical metal castings cooperatively assembled in a spring shield. Each of the castings includes a plurality of arches which coact with corresponding arches of the other casting to form separable rings suitable for holding punched loose leaf sheets in a conventional manner. Each casting further has a plurality of base elements which continuously abut corresponding base elements of the other casting in a manner to provide a locking action in either an opened or closed position as determined by the direction of over-center movement of the coacting base elements, and booster engageable webs.

It is an object of the present invention to provide a novel die cast ring metal frame of extremely simple construction having a minimum number of parts and being, therefore, susceptible to rapid and inexpensive manufacture and assembly.

Another object of the invention is to provide a device of this type requiring a minimum of structurally different elements, thereby to reduce tooling and die costs for quantity production.

Another object of the invention is to provide a device of this type which, while being relatively inexpensive to manufacture, will yet render long and efficient service of the type for which it is designed.

The foregoing and other objects and advantages are apparent from the following description taken with the accompanying drawing, in which:

Fig. 1 is a plan view of a shield encased die cast loose leaf ring metal frame constructed according to the teachings of the present invention;

Fig. 2 is a side elevational view thereof;

Fig. 3 is a bottom plan view thereof;

Fig. 4 is a vertical, transverse, cross-sectional view on substantially the line 4—4 of Fig. 2, with the ring metal frame in closed position;

Fig. 5 is a vertical, transverse, cross-sectional view on substantially the line 5—5 of Fig. 2, showing the ring metal frame in open position;

Fig. 6 is a vertical, transverse, cross-sectional view on substantially the line 6—6 of Fig. 2, showing the ring metal frame in open position;

Fig. 7 is an isometric view of a metal casting having a plurality of arches; and

2

Fig. 8 is an enlarged fragmentary end view of an arch, taken substantially on the line 8—8 of Fig. 5.

Referring to the drawings more particularly by the numerals thereon, 10 indicates generally a loose leaf ring metal frame constructed according to the teachings of the present invention. The loose leaf ring metal frame 10 includes two identical metal die castings 11 cooperatively assembled in a spring shield 12.

The castings 11 may be of any suitable material, such as a zinc base die cast metal which has been determined to produce excellent castings, and each includes a longitudinal bar 13 having transversely extending arches 14, 15 and 16, and transversely extending base elements 17, 18 and 19, the longitudinal spacing of said arches and said base elements being symmetrical with respect to a transverse centerline 20. Flat webs 21 extending outwardly from the base elements 17 and 19 and merging with these respective base elements and with extensions 22 of the longitudinal bar 13 are provided for the purpose of employing conventional "boosters" for actuating the loose leaf rings.

Except where joined by the arches 14, 15 and 16, the longitudinal bar 13 has a cross-sectional shape, as shown at 25 in Fig. 5, which cross-sectional shape 25 includes a wedge-shaped edge 26.

30 The arches 14, 15 and 16 have their free ends shaped to the configuration best shown at 27 in Fig. 1 wherein the symmetrical S form provides a self-aligning joint 27 such that, when the free ends of any two arches are appropriately opposed one to the other, the two abutting arches form a continuous arc through the joint.

The base elements 17, 18 and 19 are identical except for the treatment of their free ends. The base element 17 has a wedge-shaped end 35 and the base element 19 has a V notch 36, the base elements 17 and 19 being equi-distant from the transverse centerline 20. The angle included in the V notch 36 is greater than the angle of the wedge 35 so as to provide for cooperative action 45 between these two base elements, as will appear. The base element 18, being disposed on the transverse centerline 20, has one-half 37 of its free end shaped to a convex form and the other half 38 shaped to a concave form, so that an identical opposing base element 18 may dispose a convex half 37 in the disclosed concave half 38, and a concave half 38 may receive the disclosed convex half 37.

55 It may thus be seen that two identical castings 11, when opposed to each other as in Figs. 1

through 6, will coat one with the other to form a plurality of separable rings having self-aligning joints, said alignment being maintained transversely (with respect to the planes of the rings) by the cooperative engagement of the ends of the arches and vertically by the cooperative engagement of the ends of the base elements.

The spring shield 12 may be formed from a single strip of metal, such as steel, to have a cross-sectional shape as shown at 40 in Fig. 5. The transverse shape shown at 40 includes an arc 41 and turned-back flanges 42 to form angular recesses 43. This cross-sectional shape is continuous for a length exceeding the maximum length of the metal castings 11, except for pairs of opposed notches 46, 47 and 48. The ends of the spring shield 12 may be treated in any appropriate manner to form a finished appearance, as at 49. Holes, such as 50, may be provided for attaching the loose leaf ring metal frame 10 to a suitable binder.

In assembling the loose leaf ring metal frame 10, two castings 11 are disposed parallel to the spring shield 12 with their arches 14, 15 and 16 projecting through the appropriate notches 46, 47 and 48 and so opposed one to the other as to dispose their respective wedge-shaped edges 26 within the angular recesses 43, and further so as to dispose the ends of the base elements 17, 18 and 19 of one casting 11 in abutting relation to the ends of the other casting 11, as shown in Figs. 4 through 6. Thus assembled, the two castings 11 are maintained in cooperative engagement one with the other by the spring action of the arc 41 of the spring shield 12. It may be seen that, when the arches of the two castings 11 are separated as shown in Figs. 5 and 6, the coating base elements, such as 17 and 19 in Fig. 5 and 18 in Fig. 6, will rotate upwards about the wedge-shaped edges 43 as centers until such upward rotation of the base elements is stopped by abutment of the base elements against the arc 41 of the spring shield 12. In this manner, triangles of compressive forces are formed, the bases of the triangles being lines through the two wedge-shaped edges 43 and the sides of the triangles being the axes of the respective base elements 17, 18 and 19. The rigidity of these triangles of compressive forces is such as to firmly lock the arches in their separated positions. When it is desired to close the arches to form a continuous arc through their joints, they are merely pushed together. This causes the base elements, such as 17, 18 and 19, to rotate downward around the wedge-shaped edges 43 as centers, whereupon the wedge-shaped edges 35 of the base elements 17 rotate in the V notches 36 of the base elements 18 and the convex portions 37 of the base elements 18 rotate in the concavities 38 thereof, so as to dispose these points of abutment of the ends of the base elements 17 and 19 below the lines through the wedge-shaped edges 43 as shown in Fig. 4. When the ends of the arches are brought together, these points of abutment of the base elements lie below the line joining the wedge-shaped edges 43 so as to again form triangles of compressive forces, and thus maintain the arches in locked engagement.

The present zinc die cast ring metal frame 10

is inexpensive to make. It is sturdy and well adapted for the simple loose leaf binder of which it forms the base.

The loose leaf ring metal frame above described obviously fulfills the objects and advantages sought therefor. The description is in no sense restrictive, and the substitution of equivalent elements and principles is considered as lying within the scope of the invention.

What is claimed is:

1. In a loose leaf metal frame, in combination, a pair of identical frame members in opposed engagement, each frame member being die cast from non-ferrous metal and comprising an elongated bar, an odd plurality of ring arches cast integrally with said bar and extending transversely therefrom, one of said arches being located in a center plane midway between the ends of the longitudinal bar, the remaining arches being located in spaced symmetry on opposite sides of said center plane, and a base element for each of said arches, said base elements being cast integrally with said bar and extending transversely therefrom, each of said base elements being disposed in the plane of a respective arch, the free end of the base element in said center plane being formed non-symmetrically with respect to said center plane so as to dispose mutually complementary end surfaces on opposite sides thereof, the free ends of the base elements which are removed from said center plane being formed symmetrically with respect to the respective planes in which they lie, each base element which is removed in one direction from said center plane having a different end form than the base element which is removed equidistantly in the opposite direction from said center plane, said different end forms being such as to provide for mutual pivotal engagement, the free end of each base element on one of said frame members being in continuous engagement with the free end of a base element on the other of said frame members, the free ends of said arches being of identical form and being adapted for respective engagement with the free ends of the arches in the opposed frame member in one position of movement of said frame members, and means maintaining said frame members in opposed engaging relation and permitting overcenter pivotal movement thereof about the free ends of said base elements.

2. The combination of claim 1 wherein the non-symmetrically formed free end of the base element disposed in said center plane comprises a concave surface on one side of the center plane and a convex surface on the other side of the center plane.

PETE O. DERRINGER.
